UNITED STATES PATENT OFFICE

115,578

DESIGN FOR A PORCELAIN INSULATOR

Ludwig A. Stohl, Sun Prairie, Wis.

Application February 1, 1939, Serial No. 82,700

Term of patent 7 years

To whom it may concern:

Be it known that I, Ludwig A. Stohl, a citizen of the United States, residing at Sun Prairie, in the county of Dane and State of Wisconsin, have invented a new, original, and ornamental Design for a Porcelain Insulator, of which the following is a specification, reference being had to the accompanying drawing, forming part thereof.

In the drawing:

Figure 1 is a view of a porcelain insulator embodying my new design as it appears in side elevation.

Figure 2 is a plan view of the insulator shown in Figure 1.

I claim:

The ornamental design for a porcelain insulator, as shown.

LUDWIG A. STOHL.
